UNITED STATES PATENT OFFICE.

JAMES PASS, OF SYRACUSE, NEW YORK, ASSIGNOR TO ONONDAGA POTTERY COMPANY, OF SYRACUSE, NEW YORK, A CORPORATION OF NEW YORK.

DESIGN FOR A DISH.

SPECIFICATION forming part of Design No. 36,934, dated May 31, 1904.

Application filed May 2, 1904. Serial No. 206,086. Term of patent 7 years.

To all whom it may concern:

Be it known that I, JAMES PASS, a citizen of the United States, residing and having my post-office address at Avery avenue, in the city of Syracuse, county of Onondaga, and State of New York, have invented a new, original, and ornamental Design for Dishes.

The accompanying drawing is a top plan of a dish embodying my design.

What I claim is—

The ornamental design for a dish, substantially as herein shown.

JAMES PASS.
